WILLIAM H. BROWN, OF ROCHESTER, NEW YORK, ASSIGNOR TO HIMSELF, RICHARD TRENAMAN, AND AMI HILLS, OF SAME PLACE.

Design No. 3,585, dated July 27, 1869.

DESIGN FOR A COAL-HOD SPOUT.

The Schedule referred to in these Letters Patent and making part of the same.

To all whom it may concern:

Be it known that I, WILLIAM H. BROWN, assignor to myself, RICHARD TRENAMAN, and AMI HILLS, all of the city of Rochester, county of Monroe, and State of New York, have invented or produced a new and original Design for the Mouth or Spout of a Coal-Hod; and I do hereby declare that the following is a full and exact description thereof, reference being had to the accompanying drawings, making part of this specification, in which the figure represents a perspective view of my improved hod.

This invention consists in forming the spout or discharge-mouth of the hod with a square or plane bottom, and a curved or oval top, thereby securing a more ornamental and pleasing exterior, and at the same time rendering the hod more convenient and effective in use.

In the drawings—

A represents the hod, which, in its general construction, may be of any ordinary kind.

The spout B is formed with a square or plane bottom, a, serving as the floor for the discharge of the coal, and with a curved or oval top, b, which forms the bonnet, setting back over the body of the hod, so as to leave a very large discharge-opening.

The side edges c c are made square for a little distance back, and then are gradually merged into the curve b.

By this construction, what is known as the "bon-

net-hod," is converted into one having an ornamental spout which presents a far more ornamental and pleasing appearance than the old tunnel-spout, which is of conical or cylindrical form. The outline is rendered graceful and attractive.

In addition to the above, this construction presents several advantages, as follows:

The discharge-opening is made larger for the passage of the coal. The square floor presents less impediment to the coal than a curved one would. There is less liability of spilling the coal, for the reason that the plane bottom rests closely in the opening of the stone, while the tunnel-bottom would not. The square form enables it to be easily inserted in the side door of a stove, and the flaring angle of the top allows it to be raised square with the door, to discharge without spilling. The square bottom also allows a shovel to enter, to remove any excess of coal, or to take out only a given quantity.

By this construction, a larger outlet-surface is secured, while, at the same time, the proper proportion and beauty are retained.

What I claim as my invention, and desire to secure by Letters Patent, is—

The design for coal-hod spout herein set forth.

WM. H. BROWN.
